(57) **CLAIM**

The ornamental design for packaging for a dental component, as shown and described.

DESCRIPTION

FIG. 1 is a perspective view of packaging for a dental component according to our new design;

FIG. 2 is a top plan view thereof;

FIG. 3 is a bottom plan view thereof;

FIG. 4 is a front elevational view thereof;

FIG. 5 is a right side elevational view thereof, the left side elevational view being a mirror image of FIG. 5; and,

FIG. 6 is a rear elevational view thereof.

1 Claim, 3 Drawing Sheets
